TAPE MATCH DISPENSER AND LIGHTER

Arthur E. H. Barili and Guglielmo R. Tremolada,
Los Angeles, Calif.

Application June 29, 1932, Serial No. 619,938

8 Claims. (Cl. 67—7)

The present invention has relation to a match tape and to devices for holding, dispensing and lighting of such tape.

The matches in common use at the present day, are generally made in individual sticks or in splints. To use such matches, it is necessary to pick up or tear off each match individually and to strike its head on a suitable surface. Such matches, particularly the commonly used paper splint, are short, and, when held in the fingers to light a cigar, cigarette, or pipe, are very quickly consumed and frequently inflict burns on the fingers of the user or, at least, leave a black, sooty, unsightly mark on the finger-tips.

These, and many other disadvantages of the ordinary match are well-known by all smokers, and many efforts have been made to develop some sort of cheap and convenient device possessing the capacity of the match to function satisfactorily and being free from its disadvantages. The most commonly used device of this type comprises a container for an inflammable liquid, a wick, and means for igniting the liquid absorbed by the wick. Such devices are necessarily relatively expensive. They get out of order very easily. They are ill-smelling and quickly run dry, due to the high, volatile character of the solution used.

The device herein described and claimed may be considered a composite structure combining the advantages of the ordinary match with the desirable features of the liquid lighter above referred to, but possessing none of the many disadvantageous features of such articles.

Retaining the idea of using a match, the general object of our invention is to provide a tape made out of paper or other suitable material and having, along its surface, equidistant lumps of ignition material corresponding to the heads of the ordinary matches. Another object is the provision of a suitable container fitted to hold a roll of such match tape. A further object is the provision of means for projecting measured portions of tape from the tape roll within the container. Another object is to provide means for igniting each match lump of the tape as it shoots out of the container.

With these objects in view, our invention consists in the combinations and advantageous features fully explained in the following description and illustrated in the appended drawing, of which:

Fig. 1 is a side elevation of a device embodying the invention, the front plate or cover being

removed in order to disclose the interior mechanism.

Fig. 2 is a plan view of the device on a larger scale and with a part broken away for the sake of clearness, 5

Fig. 3 is a sectional, end elevation taken substantially on line 3—3 of Fig. 1, in the direction of the arrow,

Fig. 4 illustrates a portion of the match tape proper, and 10

Fig. 5 illustrates the simplified form of the device.

The numeral 1 denotes a shallow tray within which a cog wheel 2 is mounted for rotation, and it is positioned to mesh with propelling elements 4 of a feed drum 3. The top rim of the tray is slit, and it is noticed that a section of the cogs of the wheel 2 project beyond the tray through this slit.

The match tape is shown in Figs. 1 and 4 to comprise a strip 5 on which are deposited lumps or spots of ignition material 6. In addition, the strip is provided with equidistant perforations 7, and these perforations are spaced to register with a series of equidistant projections or teeth 8 of the feed drum 3. The tape is, in the first instance, formed into a roll, and this roll is laid into the tray whereupon, the outer, free end of the tape is passed over the surface of the drum 3 permitting at least one of the teeth 8 to seat 30 in the perforations 7. The outer end of the tape is, thereupon, passed through a slot 9 in the casing.

As above stated, the upper portion of the rim of the tray is slit to admit the upper portion of the cog wheel and this slitting is continued across the top of the tray, as a result of which, a long, slender tongue 10 is provided, the outer end of which is shown shaped to ride on the periphery of the feed drum 3, and to curve outward therefrom to the edge of the casing. On the inner surface of this outwardly curved, end portion of the tongue is provided a multiplicity of fine protrusions 11.

As above stated, the tape roll is first laid into 45 the tray and bent over the feed drum 3, and it is noted the ignition lumps are placed on the inner curve of the roll, which is bent back over the feed drum to cause these lumps to project outwardly from the periphery of the drum. When, 50 now, the cog wheel 2 is caused to revolve in the direction of the arrow 12, it is noticed that the drum 3 commences to revolve in the opposite direction, causing an ignition lump 6 to pass around the periphery of the drum until the tongue 55

10 is reached and sufficiently elevated to permit the lump to travel along the under side of the tongue and out through the slot 9. As the lump approaches this slot, it must pass the protrusions 5 11 of the tongue. The friction developed, due to the scratching of these protrusions against the ignition lump, causes the substance of the lump to ignite as it passes out through the slot.

The device of our invention is, in Fig. 1, shown 10 considerably enlarged. In actual practice, it is only about one-half the size and very thin, so as to fit conveniently within the vest pocket of a man, or the handbag of a woman. It is placed in the palm of the hand and gripped by the fingers, leaving the thumb free to partially rotate the cog wheel 2 and, as this wheel is very much larger than the intermeshing portion of the feed drum, it is noticed that a comparatively slow 15 movement of the cog wheel will revolve the drum at a speed high enough to ignite the ignition lumps on the scratch surface of the tongue.

Means should be provided to effect a step by step rotation of the cog wheel of a length to project an ignition lump each time the wheel is 20 rotated. In the drawing, this is shown accomplished merely by providing a series of equidistant perforations 13 in the cog wheel for registration with a projection 14 of the tray. In this case, the cog wheel should be sufficiently resilient 25 to slide over this projection and to snap back into line when a perforation 13 moves into registration with the projection, but, of course, more elaborate and sensitive devices may be substituted. It is important, however, that the perforations 30 13 or their equivalents be correctly spaced to advance each ignition lump a predetermined distance each time the wheel is rotated, and the mechanism should be sensitive enough to permit the operator to feel and to hear the click at the end of each movement of the wheel.

A projection 15 may conveniently be provided in the tray below the cog wheel 2, and this projection should seat in the center opening of the tape roll when the latter is placed within the tray. Without such projection, there is the danger 45 that the roll might gradually become so badly entangled within the tray that the device might fail to function properly, or the tape might break, but the stud is found to maintain the roll in position, and apparently to prevent such entanglement of the tape.

The structure hereinbefore described, is extremely simple and cheap to make. It is capable of holding a relatively very large roll of tape and, 50 as the ordinary match box, it is supposed to be thrown away when the tape has been used. As shown in Figs. 2 and 3, the tray is closed by a suitable cover 16, having a flange 17 tightly fitting the rim of the tray, but a cover plate may, 55 of course, be otherwise applied, if desired. No matter what kind of cover may be used, it is important to note that all the mechanism is mounted within the tray, and that the only function of the cover is to close the open face of the tray. This 60 construction makes it very much easier and cheaper to assemble the device than it would be if the members of the combination were assembled partly in the tray and partly in the cover.

For the sake of cheapness, the device should 70 contain as few parts as possible. It was first contemplated to employ merely a feed drum 20, as illustrated in Fig. 5, entirely eliminating the cog wheel 2. This drum is made with teeth 21 for registration with perforations 22 of the tape 75 23. A resilient tongue 24 made with a scratch

surface 25 is mounted in the casing 26 adjacent to the periphery of the feed drum. The operation of this simple device is no different from the foregoing, except that it is found difficult to rotate the feed drum rapidly enough for the 5 proper ignition of the match lump on the tape.

Where, on the other hand, more elaborate, expensive, and ornamental devices are desired, it is, of course, possible to substitute a mechanically much more refined structure without departing 10 from the scope of the combination as set forth in the following claims.

We claim:

1. A casing, a match tape seated within the casing and provided with a series of equidistant ignition lumps and intermediate equidistant perforations, a feed drum having a series of equidistant peripheral projections registering with the perforations of said tape, manual means for rotating said drum to project said tape from the 20 casing, means for yieldingly limiting the forward movement of the drum so as to project the tape step by step equal predetermined distances, and means engageable by the lumps of the tape for igniting the substance of said lumps as they pass 25 out of the casing.

2. A casing, a feed drum mounted to revolve within the casing and made with equidistant peripheral projections, a match tape seated within the casing and shaped for engagement by said 30 projections to project the tape from the casing, means manually operable from without the casing for rotating said drum, means for yieldingly determining the length of movement of said manual rotating means, lumps of ignition material 35 deposited on said tape and equidistantly spaced to correspond with the measured movement of said manual operating means, and means for igniting each ignition lump as it is projected out of the casing.

3. A casing, a roll of match tape within the casing having a series of spaced ignition lumps, a feed drum having equidistant projection engaging perforations of said tape for projecting said tape from the casing, manually operable means 45 extending through a slot in the casing for rotating said feed drum in steps of uniform length, means for igniting each lump of the tape as it is projected out of the casing, and means for guiding said roll of tape within the casing.

4. A casing, a feed drum within the casing, a match tape within the casing and provided with a series of ignition lumps, said feed drum having peripheral projections for engaging said tape to project the latter out of the casing, a 55 relatively large disk mounted to revolve within the casing and having a portion extending beyond the casing for partial manual rotation, said disk being shaped to engage members of said drum to rotate the latter at relatively high speed, and 60 means for yieldingly arresting said disk at the end of each partial rotation.

5. A casing, a relatively small feed drum in said casing, a relatively large wheel mounted in the casing to rotate said drum at relatively high 65 speed, the said wheel having a portion of its periphery extending beyond the casing for partial manual rotation, a match tape seated within the casing and bent over the said drum, said tape being shaped for engagement by equidistant peripheral projections of the said drum to project the tape from the casing as the wheel is given a partial uniform rotation, a series of equidistant ignition lumps deposited on said tape, means for igniting each lump as it is projected out 70 75 78

of the casing, means for yieldingly measuring the partial movement of said wheel to correspond to the distance between the said lumps, and means for guiding the tape within the casing.

- 5 6. A casing, a feed drum mounted to revolve in said casing, a relatively large cog wheel rotatable within the casing and having a portion of its periphery projecting through the casing 10 for partial manual rotation, the said drum being shaped for engagement by the cogs of said wheel to be revolved at relatively high speed, a roll of match tape within the casing and having its free end bent over said drum, said tape being made 15 with a series of equidistant ignition lumps, a resilient member on said casing and having a scratch surface for engagement by the lumps of said tape as they pass out of the casing, means for yieldingly measuring the partial rotation of said 20 cog wheel to correspond to the distance between the said tape lumps, and means for guiding the tape within the casing.

7. A tray, a roll of tape within the tray and made with equidistant ignition lumps, a feed drum mounted to revolve within the tray, said drum having equidistant peripheral projections engaging said tape for projecting the free end of the tape through a slot in the tray rim, a hand-wheel in the tray for rotating said drum at rel-

atively high speed, said hand-wheel having equidistant perforations engageable by a member of said tray yieldingly to limit the rotation of the wheel to turn said drum distances equal to the distance between said ignition lumps, said wheel 5 having a portion of its periphery projecting through a slot in the rim of the tray for manual partial rotation, the portion of the rim which has been separated to produce said slot being bent to form a tongue the outer end of which 10 is provided with a scratch surface positioned in the path of movement of the lumps on the tape as they are projected out of the tray, and a cover for closing the open face of the tray.

8. A casing, a feed drum mounted in the casing 15 with a portion of its periphery projecting through an opening in the casing and provided with equidistant peripheral projections, a resilient tongue having a scratch surface resting on the drum periphery at said opening, a tape freely 20 seatable in the casing, said tape having perforations for registration with said projections and provided with equidistant ignition lumps intermediate said perforations, and means for positively advancing said tape in uniform steps equal 25 to the distance between said perforations.
